BICYCLE STEERING POST

Carlton P. Pawsat, Maysville, Ky., assignor to Wald
Manufacturing Company, Inc., Maysville, Ky.

Continuation-in-part of abandoned design applications Ser.
No. 22,184 and Ser. No. 22,185, both Apr. 1, 1970.
This application Nov. 5, 1970, Ser. No. 26,362

Term of patent 14 years

Int. Cl. D12—11

U.S. Cl. D90—9

FIG-1

FIG-2

FIG-3

FIG-4

FIG-5

FIG-6

FIG. 1 is a side elevational view of a bicycle steering post showing my new design.

FIG. 2 is a front elevational view thereof as seen from the left side of FIG. 1.

FIG. 3 is a top elevational view thereof.

FIG. 4 is a side elevational view of a modification of my design.

FIG. 5 is a front elevational view thereof as seen from the left side of FIG. 4.

FIG. 6 is a top elevational view of FIG. 4.

This is a continuation-in-part of petitioner's design patent applications, Ser. Nos. D.22,184 and D.22,185, both filed on Apr. 1, 1970, and now abandoned.

I claim:

The ornamental design for a bicycle steering post, as shown and described.
